[57] **CLAIM**

The ornamental design for a troll lure, as shown and described.

DESCRIPTION

FIG. 1 is a perspective view of a troll lure showing my new design;

FIG. 2 is a front elevational view thereof;

FIG. 3 is a left side elevational view;

FIG. 4 is a right side elevational view thereof;

FIG. 5 is a rear elevational view thereof;

FIG. 6 is a top view thereof; and,

FIG. 7 is an additional perspective view thereof.

The broken line showing of the hook in FIGS. 1-5 and 7 is for illustrative purposes only, merely disclosing the types of attachments which can be used, and forms no part of the claimed design. The broken line showing of the fishing line in FIGS. 1 and 7, and the water in FIG. 7 is for illustrative purposes only and forms no part of the claimed design.
